UNITED STATES PATENT OFFICE.

CHARLES F. MURRAY, OF CHICAGO, ILLINOIS, ASSIGNOR OF ONE-THIRD TO WILLIAM V. KELLEY AND ONE-THIRD TO ROBERT P. LAMONT, BOTH OF CHICAGO, ILLINOIS, AND ONE-THIRD TO WILSON W. BUTLER, OF NEW YORK, N. Y.

SIDE FOR RAILWAY-CARS.

1,009,987.

Specification of Letters Patent. Patented Nov. 28, 1911.

Application filed December 11, 1909. Serial No. 532,607.

To all whom it may concern:

Be it known that I, CHARLES F. MURRAY, a citizen of the United States, residing at Chicago, in the county of Cook and State 5 of Illinois, have invented certain new and useful Improvements in Sides for Railway-Cars, of which the following is a specification.

The purpose of the present invention is to 10 maintain tight the joints or seams between boards or planks disposed edge to edge to form a wall, the invention being particularly adapted for employment in connection with the walls of railway box-cars, though it 15 should be understood that it is not limited or restricted to this particular use.

As is well known, lumber has a decided tendency to shrink and contract transversely, and when a car-body wall is made of a 20 single thickness of boards or planks, unless some especial means is provided the joints or seams between such boards have a tendency to open up, offering means for a loss of the contents of the car, provided the 25 same is composed of small particles such as grain, and offering access of the outer air to the interior of the car.

It is to overcome or off-set the detrimental features occasioned by such shrinking that 30 I have produced the invention herein set forth, which, briefly stated, comprises the employment of automatically expandible means associated with such board seams so as to maintain the same closed even though 35 the boards shrink to a considerable extent.

In the accompanying drawing, which forms a part of this specification, I have indicated two desirable embodiments of the invention, although the latter is susceptible 40 of a considerable number of others.

In this drawing—Figure 1 is a fragmentary face view of a wall, such as that of a railway car-body, composed of boards or planks disposed edge to edge and provided 45 with one style of my improved means for keeping closed such joints or seams between the boards; Fig. 2 is a vertical cross-section through the wall construction shown in Fig. 1, and indicates the relation of the parts 50 before shrinkage occurs; Fig. 3, which is an enlarged cross-section of a portion of the wall, shows the manner in which the expandible insert or filler keeps the joint or seam closed after the shrinkage has taken

place; Fig. 4 is a fragmentary elevation of a 55 part of the wall incorporating a modified embodiment of the invention; Fig. 5 is a vertical cross-section through such wall; and Fig. 6 is a view similar to Fig. 3 illustrating the manner in which this particular form 60 of expandible metal strip acts to keep the joint closed after the shrinkage has occurred.

Referring again to Fig. 1, it will be noticed that the wall, as for instance the side or end wall of a railway car-body, is composed of a number of boards or planks 10 disposed edge to edge, and in the present instance arranged horizontally, although such disposition in no way affects the invention. The opposite longitudinal edges of such 70 boards are recessed or grooved at 11 in the form and style shown clearly in Fig. 3 so as to accommodate between them in each joint a sheet-metal automatically expanding spring hollow strip or body 12 of general cross 75 shape in cross-section and split or divided longitudinally at one point 13, whereby to permit the automatic expansion referred to. Preferably, though not necessarily, this divided split or slit is disposed inwardly of the 80 car-body wall, for the obvious purpose of having the exterior of the wall present a neater appearance, and to prevent the entrance of dirt, rain, etc., to the interior of such strip. When the wall is first constructed, the boards 85 10, 10 are placed practically in contact with the expandible metal strips housed in the registering and matching grooves or recesses of the boards, such strips, when the wall is first formed, being contracted as indicated 90 in Fig. 2, so that when the boards tend to shrink these fillers may automatically expand, owing to their spring action, so as to maintain closed the joints between the boards, as is indicated clearly in Fig. 3. 95 Of course, these spring fillers need not be of the particular shape in cross-section shown in the drawing, since a considerable variety of styles and shapes would satisfactorily perform the required function. It 100 has been found, however, that this style and shape of filler will successfully accomplish the result required.

In Figs. 4, 5 and 6 a different embodiment of the invention is illustrated, and in this 105 case the boards or planks 14 are longitudinally grooved at 15 along only one edge, so that such grooved edge in the wall is in

proximity or adjacent to the flat edge 16 of the next board or plank. In such seams or joints between the boards when the wall is constructed I interpose automatically-expanding sheet-metal spring fillers 17, which when inserted have the oppositely-extended flanges 18 lying against the flat edge 16 of the board, such strip having along its longitudinal center a V-shaped rib 19 housed or received within the groove 15 of the next board. When a wall of this kind is erected these fillers or inserts are compressed somewhat out of their normal shape to that shown in Fig. 5, whereby when the boards or planks shrink laterally these inserts or fillers can expand to take their normal shape shown in Fig. 6, and because of such automatic expansion they keep the joints between the boards closed at all times.

Having indicated two embodiments of the invention, I desire to direct attention to the

fact that many other forms of the filling strips may be used without departing from the heart and essence of the invention and without the sacrifice of any of its substantial benefits. 25

I claim:

A wall, comprising, in combination, a plurality of boards placed edge on edge, at least one abutting edge of each board being 30 grooved, and spring-joint closing strips disposed between said boards, each strip having a portion extending into a groove in one of said boards to prevent displacement of said strip, and said strip having portions extending to the sides of the board for the purpose of sealing the joint. 35

CHARLES F. MURRAY.
